UNITED STATES PATENT OFFICE.

GEORGE THOMAS LIDDLE, OF MUSKEGON, MICHIGAN.

BOTTLE.

No. 802,400.

Specification of Letters Patent.

Patented Oct. 24, 1905.

Application filed May 29, 1905. Serial No. 262,857.

To all whom it may concern:

Be it known that I, GEORGE THOMAS LIDDLE, a citizen of the United States, residing at Muskegon, in the county of Muskegon and State of Michigan, have invented new and useful Improvements in Bottles, of which the following is a specification.

This invention relates to bottles of the breakable-neck type, and has for its objects to produce a simple inexpensive device of this character which will effectually prevent the fraudulent reuse of the bottle, and consequently the employment of the latter for the sale of a grade of goods inferior to that which it originally contained.

Further objects of the invention are to provide a device of this character wherein after application of the seal the latter cannot be removed or the cork extracted without breaking the neck, thus destroying the original appearance and integrity of the bottle, and one wherein the seals may be preserved unimpaired for repeated use.

With these and other objects in view the invention comprises the novel features of construction and combination of parts more fully hereinafter described.

In the accompanying drawings, Figure 1 is a central section through a portion of a bottle and its neck, the latter having applied thereto a seal embodying my invention. Fig. 2 is a perspective view of the body of the seal. Fig. 3 is a similar view of its retaining member. Fig. 4 is a view similar to Fig. 1, showing another embodiment of seal applied for use. Fig. 5 is a side elevation of the body of the seal shown in Fig. 4, and Fig. 6 is a perspective view of the retaining member employed in connection therewith.

Referring to the drawings, 1 designates a bottle having a neck 2, designed to receive a cork 3, these parts all being of the ordinary construction and adapted to perform their usual functions, except the neck 2 is provided with a supplemental portion or extension 4 of a thin highly-frangible formation at its point of juncture 5 with the main portion of the neck and having on its interior a series of downwardly-pitched engaging portions or teeth 6 preferably extending wholly around the inner face of said extension and appropriately spaced in a direction longitudinally of the latter, it being noted that the inner diameter of the neck portion 4 is slightly greater than that of the neck portion 2 for a purpose which will hereinafter appear.

Arranged in the portion 4 of the neck is a sealing member 7, which, as illustrated in Figs. 1 to 3, comprises a cylindrical body composed of any suitable material and having a transverse opening 8, designed to receive a retaining member or spring 9, provided with outturned spring-engaging portions or fingers 10, adapted for engagement with the teeth 6 to hold the body 7 in place, the member 9 being carried and maintained in position within the opening by a wedge-like block or element 11, having upwardly-convergent side edges, producing within the body suitable cavities or recesses 12 to receive and permit relative compression of the spring-fingers 10 during introduction of the seal into the bottle-neck.

In practice after the bottle has been filled and the cork 3 inserted in place, which latter may be readily accomplished owing to the neck portion 4 being of larger diameter than that of portion 2, the seal 7, together with its retaining member 9, is introduced into the neck and forced downward until it seats upon the upper end of the cork, in which position it will be retained owing to engagement of the fingers 10 with one of the teeth 6, thus preventing its own removal or that of the cork. It is to be noted at this point that the body 7 is of a diameter equaling that of the neck portion 4, whereby it cannot be forced downward through the neck 2, and, further, will prevent insertion of a wire or other instrument for tampering with the retaining-fingers 10. When it is desired to open the bottle, the neck is fractured, usually at the point 5, whereupon the cork 3 may be extracted in the ordinary manner and the seal readily removed from the neck portion 4 and preserved for repeated use.

In the form of device illustrated in Figs. 4 to 6 the body or seal 7 is provided with a headed stud 13 and the retaining member 9 with a base portion 14, having a seat 15 to receive said stud, there being formed in the side of the body 7 at diametrically opposite points recesses 16 to receive and permit play of the spring-fingers 10 during insertion of the seal. In other respects the construction and operation of the device is identical with that above described.

From the foregoing it is apparent that I produce a simple inexpensive device of this character which in practice is admirably adapted for the attainment of the ends in view, it being understood that minor changes

in the details of construction may be resorted to without departing from the spirit of the invention.

Having thus described my invention, what

5 I claim is—

A bottle and its neck, the latter comprising stopper and seal receiving portions, the latter portion having internal teeth and being of greater diameter than the stopper-receiving portion, a sealing-body adapted for entrance into the neck, and a retaining member having

a yieldable finger for engagement with the teeth to retain the body in place, said body having a recess to receive and permit play of the finger.

In testimony whereof I affix my signature in presence of two subscribing witnesses.

GEORGE THOMAS LIDDLE.
